UNITED STATES PATENT OFFICE.

CHARLES BENJAMIN FRANKLIN, OF PINEVILLE, LOUISIANA.

BURIAL VAULT.

1,415,435.

Specification of Letters Patent. Patented May 9, 1922.

Application filed April 29, 1921. Serial No. 465,395.

To all whom it may concern:

Be it known that I, CHARLES B. FRANKLIN, a citizen of the United States, and a resident of Pineville, in the parish of Rapides and 5 State of Louisiana, have invented certain new and useful Improvements in Burial Vaults, of which the following is a specification.

This invention relates to burial vaults. 10 The object of the invention is to provide forms by which a ready-to-use water-proof vault for burial caskets may be molded or cast.

It is also an object of the invention that 15 the forms be adapted to mold burial vaults of different lengths.

Other objects and objects relating to details of construction, combination and arrangement of parts will hereinafter more 20 definitely appear in the detailed description to follow.

The invention is illustrated by way of example in the accompanying drawings, in which:

25 Figure 1 is a top plan view of the forms when assembled for molding,

Figure 2 is a central longitudinal vertical section of the same,

30 Figure 3 is a view similar to Figure 2, but showing the cement after the same has been poured for forming a burial vault,

Figure 4 is a transverse vertical section taken substantially on the lines 4—4 of 35 Figure 1, and also showing the cement board for forming the burial vault,

Figure 5 is a detail perspective view of an end portion of a burial vault after it has been lifted from the forms in which it was molded,

40 Figure 6 is a perspective view of a lid for the vault,

Figure 7 is a detail view illustrating the sealing of the vault by its cover or lid.

Referring to the drawings more particularly, 45 10 indicates a floor or platform which, in the present instance, is covered with a thin sheeting of tin 11. Upon the sheeting of tin there rests an inner form generally indicated at A. This form is rectangular in 50 cross section and comprises two sections 11 and 12, the section 12 being shorter than the section 11, and also its side walls telescoping the side walls of the section 11, as clearly shown in Figure 2. Each section 11 and 12 55 comprises a pair of side plates 13, end plate 14, and a top plate 15, the respective plates

forming the corresponding walls thereof. The plates of each section are secured together by angle members as at 16. Also the side plates 13 of the section 11 are braced by 60 angle members as at 17. Each section is also provided with a pair of eye bolts Figure 2, one adjacent each side thereof. Each pair of eye bolts are in alinement with each other so that a rod (not shown) may be passed 65 therethrough to be used in lifting the form A as a whole.

About the form A there is positioned an outer form generally indicated at B. The form B likewise comprises two sections 18 70 and 19, the section 19 being the shortest, and its sides telescoping the sides of the section 18 similar to the sections constituting the form A. The form B is also rectangular in cross section; and the sections 18 and 19 75 each comprise a pair of side plates 20 and an end plate 21. The plates forming each section and likewise representing the walls thereof, are secured together and braced by angle irons in a manner similar to that of 80 securing together the plates forming the sections of the form A. In the case of the mold A, the angle irons for securing the different plates together are disposed on the interior surface of the mold, while in the case of the 85 mold B, these same angle plates are disposed on the exterior surface of the mold, this for the purpose that the adjacent walls of said molds shall present a smooth surface. Also the rivets used in securing the angle irons 90 in position are preferably counter-sunk for the same purpose.

In order to further reinforce the sides 20 of the sections 18 and 19 of the mold B I provide a pair of side members 23, which 95 when bolted to cross beams 24 are adapted to slide over the side plates 20 of the two sections, as shown in Figure 1. The side members 23 are each formed with a groove 25 adapted for receiving the upper ends of the 100 braces 26, said braces being secured at their lower ends to the angle irons 22. Also there may be secured to the floor adjacent each end of the form B a cross beam 27, the purpose of which will be to further brace the 105 ends of the form B. The end and side plates forming the walls of the forms A and B are interspaced as shown in Figures 2 and 4, and in between the lower edges of said walls there is interposed a substantially triangular-shaped mold 28. The mold 28 is preferably 110 hollow and comprises two sections, one tele-

scopic within the other as indicated at 29, Figure 3. The object of making the mold 28 extensible is of course obvious in view of the fact that the molds A and B are both extensible.

In molding the burial vaults, the space between the walls of the two forms A and B is filled with cement or a similar plastic material adapted for the same purpose and allowed to set. When the cement has set and is lifted as a whole from the forms, a burial vault 30 as shown in Figure 5, is produced. The V-shaped groove 31 also shown is of course formed by the triangular shaped mold 28. The reinforcing rods 32 are of course positioned in between the walls of the molds previous to the pouring of the cement.

It may be here pointed out that the end walls of the inner and outer forms are in the same spaced relation as the side walls thereof. This same relation of the walls is maintained when burial vaults of different lengths are formed.

As a closure for the vault, I provide a lid or cover 33, as shown in Figure 6. The cover has a substantially V-shaped projection 34 formed about its bottom edge which is adapted to extend into the V-shaped groove 31, as shown in Figure 7. The lid or cover 33 may likewise be formed in different lengths by providing a mold which is longitudinally extensible, as has been shown

and described for forming the burial vault 30. Also reinforcing strips may be inserted in the cover 33, as at 35.

When it is desired to hermetically seal the vault grout is poured into the groove 31, and then the lid 33 placed in position. A layer of grout will then be formed between the surface of the V-shaped projection 33 and the groove 31, thus hermetically sealing the burial vault.

I claim:

1. In combination, an outer form and an inner form, a pair of telescopic sections constituting each of said forms, whereby the length thereof may be adjusted, and the interspacing between their end walls made to correspond with the interspacing between their side walls, and a triangular shaped mold interposed between the said end walls and side walls comprising two telescopic sections whereby the triangular shaped mold may be adjusted with the outer and inner forms.

2. In combination, an outer form and an inner form, the side walls of which are telescopic for adjusting the length thereof, and a triangular form interposed between the said side walls and end walls at the lower edges thereof, the triangular form comprising sections adapted to permit the length thereof to be adjusted.

CHARLES BENJAMIN FRANKLIN.
